George Palmer of Brooklyn N.Y.

DES 1938

Letters Patent No. 77938. Dated Sept. 26, 1861.

Design for an Aquarium or Fish Tank.

The schedule referred to in these Letters Patent and making part of the same.

To all whom it may concern:

It is known that I, George T. Palmer, of the City of Brooklyn, County of Kings and State of New York, have invented or produced a new and original design for an Aquarium or tank to contain fish and water plants and a pedestal for the same: and I do hereby declare that the following is a full and exact description of the same. The peculiar feature of the design of the aquarium is the adaptation of the general figure and outline of a vase, with plane oval openings in which glass is inserted for the purpose of an aquarium, as shown by the accompanying drawing. Fig. 1 represents the vase aquarium, which is made of cast metal having a flat oval opening (fig. 2) at two opposite sides. Also a frame or rim for the reception of the glass. Fig. 3 represents a top view of the vase aquarium. Fig. 2 is the opening at the top of the aquarium.

Fig. 4 is a representation of a hollow bridged rock with apertures or small openings on its surface. (Fig. 3, 2, 8) The rock is formed of pottery or baked clay, the hollow interior to be filled with earth, and the water plants to be set in it through the small openings on the surface, and thereby preserving their most natural condition of being attached to the earthy bottom of sides of pores). Fig. 5 represents the pedestal for holding an Herbarium or case for containing land plants that thrive in a moist atmosphere - they form a parallelogram with octagon corners, having therein openings for glass (fig. 6) the form giving strength to the frame, and the glass in the corner an appearance of lightness.

Fig. 6 represents glass which is hermetically attached to the frame work; the

frame work is airtight hermetically attached to the bottom leaving access to the interior, at the top, which is provided with doors or removable glass covers.

(fig.6,6) which occupy the space . . . between that occupied by the foot of the aquarium and the outer edge of the herbarium pedestal.

What I claim as my invention is, the design for an aquarium

as shown and described.

month day of June, eighteen hundred and sixty-four.
